CONTROL MECHANISM FOR WRINGER ROLLS OF A WASHING MACHINE

Peter Eduard Geldhof, Syracuse, N. Y., assignor to Easy Washing Machine Corporation, Syracuse, N. Y., a corporation of Delaware

Application November 27, 1933, Serial No. 699,937

9 Claims. (Cl. 68—32)

This invention relates to new and useful improvements in the drive mechanism for roll type wringers for clothes washing machines, and pertains more particularly to the means for controlling the operation of the rolls.

The main object of this invention is to provide a power-operated roll wringer for clothes washing machines or the like, with power-operated means which may be controlled by a very slight manual effort for disconnecting the rolls with the drive mechanism.

Another object of the invention is to provide a roll wringer with means controlled by the conventional safety roll release device for disconnecting the wringer rolls with the drive mechanism whereby the rolls will cease to rotate the instant the pressure on the rolls is released.

A further object of the invention is to provide a drive mechanism for a roll wringer of the above-mentioned class which is compact, sturdy and economical in construction and that is positive and simple in operation.

In carrying out the above-mentioned objects, I have provided the conventional drive mechanism for a roll wringer comprising a drive shaft, two drive pinions arranged in opposed relation and a reversing member or clutch driven by the drive shaft and manually movable into engagement with the pinions for determining the direction of rotation of the rolls, with a neutralizing member which is operably connected with the reversing member. The neutralizing member is, in turn, operated for returning the reverse mechanism to a neutral position for disconnecting the rolls with the drive means by a power-operated device comprising a clutch member which is brought into operative connection with the drive shaft to be driven thereby by manually controlled means adapted to be operated by a very slight touch of the finger-tip and which is so positioned as to be readily accessible to one operating the washing machine. Further, the clutch control means is so connected with the conventional safety means for quickly releasing the spring tension on the rolls that the reversing member will be automatically moved to the neutral position and the rotation of the rolls thereby stopped when the safety means is operated.

Other objects and advantages pertaining to the details of the structure and the form and relation of the parts thereof, will more readily appear from the following description taken in connection with the accompanying drawings in which:

Figure 1 is a side elevation of a roll wringer embodying the various features of this invention

and a portion of the upper end of a washing machine vat with parts thereof broken away and shown in section.

Figure 2 is an enlarged detail horizontal sectional view taken in the plane of the line 2—2, Figure 1.

Figure 3 is a vertical sectional view taken substantially on line 3—3, Figure 5, looking in the direction indicated by the arrow.

Figure 4 is an enlarged detail sectional view illustrating the manner of connecting one end of the wringer head with the side of the frame.

Figure 5 is an enlarged longitudinal sectional view of the gear case and the adjacent end of the wringer.

Figure 6 is a horizontal sectional view taken substantially in the plane of the line 6—6, Figure 5.

Figure 7 is a vertical sectional view taken on line 7—7, Figure 5.

Figure 8 is a horizontal sectional view taken on line 8—8, Figure 5.

Figures 9 and 10 are detail sectional views taken respectively on lines 9—9 and 10—10, Figure 8.

The device, as illustrated in the drawings, comprises a roll wringer 1 secured at one side to a transmission case 2 and a washer vat or tub 3. The case 2 contains substantially all the mechanism comprising my invention and is mounted upon the upper end of a tubular drive shaft housing 4 adapted to contain the usual drive shafts 5. The housing 4 may be connected at its lower end to the frame, not shown, of the washing machine in any well-known manner, and as illustrated more particularly in Figure 1, has the upper end thereof secured to the washing machine vat 3 by a bracket 6.

The wringer 1 consists of a pair of rollers 7 and 8 mounted in the conventional manner one upon the other in a frame composed, in this instance, of sheet metal stampings. The frame, as shown, comprises two vertically disposed end members 9 and 10 substantially U-shaped in cross section and which are tied together at their lower ends by a suitable cross member 11. An upper cross member or head 12, also of substantially U-shaped formation, is mounted upon the upper ends of the side members 9 and 10 and is detachably connected at one end with one of the side members as 9 by a catch arrangement indicated at 13 formed by pressing adjacent portions of the head and side member outwardly, in the manner shown more clearly in Figure 4. The other end of the head 12 is pivotally connected 55

by a bolt 14 to the upper end of a U-shaped lock bar 15 positioned in the end member 10 and which is designed to releasably secure the head in place, in a manner hereinafter more fully explained.

The rollers 7 and 8 are mounted in suitable bearings provided in the frame sides 9 and 10, and as shown in Figure 5, the bearing as 17 for the lower roll is mounted in a swinging U-shaped bracket 18 which is supported on a transverse rod 19 mounted in the frame end 10 above the roll shaft 20. The upper roll is guided in the frame by bearing members 21 which engage the upper surface of the shaft 22 of the roll. The upper roll is yieldingly pressed into engagement with the lower roll 7 with greater or less pressure as determined by a pressure spring 24 extending longitudinally through the head 12, with the ends thereof resting upon the upper face of the upper roll bearings 21 and a tension screw 25 screw-threaded in the head 12 intermediate the ends thereof, as shown in Figures 1 and 5.

The wringer 1 is secured to the case 2 by a pair of screws 27 which pass through registering holes formed in the side walls of the case 2 and a pair of outwardly bent flanges 28 formed on the frame end 10. The case 2 is a substantially rectangular box-like member formed with the side thereof opposite the wringer open, while a cover member 30 is secured to the case 2 for closing said open side. The case 2 has a pendent boss 31 provided with a shaft opening 32 which rotatably receives the upper end of the tubular housing 4 therein. The lower end of the boss 31 engages an outwardly extending annular flange 4' formed on the housing 4 a short distance below the upper end thereof for limiting the downward movement of the case 2 on the housing 4.

It will thus be seen that the case 2 and wringer 1 are rotatably supported by the housing 4 in a predetermined plane above the washer vat 3 in such a manner that the wringer may be readily swung in a horizontal plane about the housing as a pivot from a position over the vat 3 to a number of predetermined positions at one side of the vat. The case and wringer may be releasably secured in the adjusted position by any suitable means as the spring-actuated lock pin 34 mounted in the boss 31 for engagement with a selected one of a plurality of circumferentially spaced holes 35 provided in the upper end of the housing 4.

The hereinbefore-mentioned drive shaft 5 may be driven in the conventional manner from the motor, not shown, usually mounted beneath the washer vat 3 for operating the washing mechanism, while the upper end of the shaft has a pin and slot connection, as indicated at 36, with the lower end of a vertically disposed stub shaft 37 which extends upwardly into the case 2, as shown in Figure 5, so that the wringer and case may be readily removed from the housing 4 by a vertical movement thereof after the lock pin 34 has been withdrawn from holding engagement with the housing 4.

The stub shaft 37 is journaled at its upper end in a pendent hollow boss 38 formed integral with the upper wall of the case 2 and intermediate its ends in a bronze bearing member 39 secured by a press fit or otherwise in the shaft opening 32 in the lower wall of the case. Rotatably mounted on the shaft 37 is a pair of opposed beveled pinions 40 arranged in longitudinal spaced relation and which are in constant mesh with a beveled gear 41 journaled in the case 2. The manner of

mounting the gear 41 in the case consists, in this instance, in providing the gear with an extended hollow hub 42 and rotatably mounting the same in a hollow boss 43 provided in a vertical wall or partition 44 formed in the case 2.

The gear 41 is operably connected with the lower roll 7 for driving the same by means of a flexible drive coupling 45 positioned in the gear hub 42 and which has a pin and slot connection as at 46 and 47 with the lower roll shaft 20 and gear 41 respectively. It will be noted that this particular connection between the gear 41 and the roll 7 not only permits a limited amount of lateral movement of the roll relative to the gear, but provides for the ready removal of the wringer from the housing 2.

Each of the pinions 40 is provided on the inner face thereof with inwardly extending clutch elements 40' adapted to be engaged by similar clutch elements 48' provided on opposite ends of a clutch member 48 which is slidably mounted upon the shaft 37 intermediate the pinions 40 for the purpose of transmitting motion from the shaft 37 to said pinions, said clutch being keyed to the shaft 37 as at 49 so that the clutch will be positively driven by the shaft 37.

In order that the clutch member 48 may be moved into and out of engagement with the clutch elements on the pinions 40, I have provided said clutch member with a peripheral annular groove 50 adapted to receive therein a roller stud 51 which is mounted eccentrically on a shaft 52 journaled in the cover 30, as shown more clearly in Figures 1, 5, and 7. In order that the shaft 52 and clutch 48 may be manually operated, one end of the shaft 52 is extended through the cover 30 and has secured thereto a lever 53.

It will here be observed that the mechanism thus far described is constructed and operates in the conventional manner to rotate the wringer 40 rolls 7 and 8; that is, the clutch 48 is positively driven by the shaft 37 which, in turn, is rotated by the constantly rotating drive shaft 5 and the wringer rolls may be rotated in one direction or the other, as desired, by moving the handle 53 45 to bring the clutch into operative engagement with one or the other of the pinions 40 depending upon the desired direction of rotation of the rolls.

In order that the power for driving the wringer rolls 7 and 8 may be utilized for moving the clutch 48 out of clutching engagement with either of the pinions 40 into a neutral position intermediate said pinions, I have provided a neutralizing member or plate 55 which is mounted in a horizontal plane beneath the lower pinion 40, as shown more clearly in Figures 5 and 6, near the lower end of the case 2. This plate 55 extends from near the outer wall of the case to within a short distance of the wringer frame and is pivotally connected at its inner end to the case 2 60 by means of a shouldered stud 57 mounted in a bracket 58 which, in turn, is secured by screws 59 to the lower end of the wall 44.

The plate is provided with an opening 56 therethrough adapted to receive the shaft 37. This opening, as shown in Figure 6, is substantially larger than that of the shaft 37 to permit the necessary rocking movement of the plate about the pivot 57. The outer end of the plate is provided with a plurality of upwardly extending rack 70 teeth 60 arranged concentrically with the pivot 57 and which are in meshing engagement with similar gear teeth 61 provided on the lower end of a segmental gear member 62 which is pivotally mounted in a vertical plane upon a stud 75

63 secured in the cover 30. This segmental gear member is also provided with a plurality of gear teeth 64 arranged in the edge thereof above the stud 63 and which are in meshing engagement with the teeth of a gear member 65 secured to or made integral with the clutch control shaft 52 so that any swinging movement of the plate 55 about the stud 57 will produce a corresponding axial movement of the clutch 48 along the shaft 10 37 through the medium of the segmental gear member 62, gear 65 and roller 51.

In order that the neutralizing plate 55 may be swung about the stud 57 as a pivot by power means, I have provided a clutch member as 67 15 mounted upon the shaft 37 intermediate the plate 55 and the bearing member 39. This clutch member is comprised of a ratchet collar 69 which is keyed to the shaft 37 as at 70, Figure 8, to be driven by the shaft. The ratchet collar is mounted adjacent the upper end of the bearing member 20 39 and a clutch plate 71 is loosely mounted on the shaft 37 intermediate the ratchet collar 69 and the neutralizing plate 55.

The plate 71, in this instance, is circular in 25 plan view and has the peripheral edge thereof provided with a groove 72 which receives one end portion of a spring member 73 which has the other end secured to the case 2 by means of a screw 74. The spring 73 is tensioned inwardly 30 toward the clutch plate 71 for yieldingly engaging said plate and frictionally maintaining the same against rotary movement.

In order that the plate 71 may be driven by 35 the ratchet 69, I have provided a pawl 76 which is slidably mounted in a radially extending slot 77 provided in the undersurface of the plate 71 for movement into and out of engagement with a plurality of, in this instance four, circumferentially spaced slots 69' provided in the periphery 40 of the ratchet collar 69. In order that the pawl 76 may be moved into and out of engagement with the collar 69, I have provided an actuating arm 79 which is pivotally connected intermediate its ends as at 80 to the clutch plate 71 in spaced 45 relation to the slot 77 so that said arm will extend across the pawl 76. The actuating arm 79 in this instance, is an arcuate member having the ends thereof terminating at substantially diametrically opposite sides of the plate 71 and said 50 ends are provided with lateral projections or stops 81 and 82 respectively which extend downwardly below the clutch plate 71.

In order that the control arm may engage the pawl 76 for actuating the same, I have provided 55 said pawl with a longitudinally extending slot as 76' in the lower face thereof adapted to receive the adjacent portion of the control arm 79. This slot 76' is of somewhat greater length than the width of the arm 79 contained therein to permit a limited amount of lost motion of the arm in said slot for a purpose about to be explained.

The end of the arm 79 mounted in the slot 77' is yieldingly urged inwardly toward the collar 69 by means of a tension spring 84 which has one 60 end hooked into the flange 82 and the other end secured to the plate 71.

It is now obvious that the spring 84 acting 65 upon the arm 79 to rock the arm inwardly about the pivot 80, normally causes said arm to maintain the pawl 76 in clutching engagement with the ratchet collar 69. In order to cause the pawl to be moved out of clutching engagement with the ratchet collar, I have provided a detent 86 70 positioned in a slot 2' provided in the bottom 75 of the case 2 and pivotally mounted on a pin or

rod 87 for movement into and out of the path of movement of the end flanges or abutments 81 and 82 on the actuating arm 79. The detent 86 is yieldingly urged upwardly into the path of the abutments 81 and 82 by a compression spring 88 5 seated in a bore 89 provided in the case 2, with the lower end of the spring resting upon a stop pin 90. The upward movement of the detent is limited by a horizontally disposed control rod 92 which extends transversely through the case 2, 10 with the ends thereof terminating outside the case.

The control rod 92 is mounted for sliding movement in guide openings formed in the side walls of the case and in a pair of spaced inwardly extending lugs 93 formed integral with the bottom wall of the case and arranged one at either side of the slot 2', (see Figures 5 and 8). The control rod 92 is provided with a cam section substantially midway between its ends consisting of a 15 pair of opposed axially spaced outwardly tapered or conical cam surfaces 95 which are connected by an intermediate flat or cylindrical surface 96. The rod is yieldingly maintained in the normal position with the intermediate surface 96 in alignment with the detent 86 by a pair of relatively light compression springs 97 mounted on the rod, one at either side of the lugs 93 between a respective lug and a washer 98 which abuts against a shoulder 99 formed on the rod at a corresponding end portion thereof. The intermediate surface 96 is so proportioned that when the control rod is in the normal position, said surface will be engaged by the detent 86 and coat with the spring 88 for maintaining the detent in the path of movement of the end flanges or abutment members 81 and 82 of the clutch actuating arm 79, and obviously, when the control rod is moved axially in either direction from the normal position, the detent will be rocked against the action 20 of the spring 88 out of the path of movement of the arm 79 by the corresponding cam surface 95. 25

As shown more clearly in Figure 8, each end of the rod 92 is provided with an enlarged head portion 92' which forms convenient finger pieces by 30 which the rod may be pushed inwardly and are so axially spaced as to form stops adapted to engage adjacent sides of the case 2 for limiting the inward movement of the rod.

It will now be readily understood that when 35 the shaft 37 and clutch collar 69 are rotated in a clockwise direction, as indicated by the arrow X in Figure 8 and the clutch control arm 79 is positioned as illustrated by full lines in said figure, and the actuating arm 79 is released by the movement of the detent 86 out of engagement with one of the abutment members as 81, the pawl engaging end of said arm will then be drawn inwardly by the spring 84 and the pawl 76 will be moved thereby into holding engagement with the ratchet 40 collar by the entrance of the pawl into the first slot 69' which is aligned with the pawl, after which the arm 79 and clutch plate 71 will be driven by the ratchet collar. This movement of the clutch elements in unison will continue until 45 an object, as the detent 86, appears in the path of one or the other of the abutment members 81 or 82 to interrupt the rotation of the actuating arm. 50

As the end of the arm is thus held by the detent, the continued rotation of the clutch plate 71 and pivot 80 will cause the pawl engaging end of the arm to swing outwardly against the action of spring 84 and withdraw the pawl from engagement with the clutch collar. The instant the 55

driving connection is broken between the pawl and ratchet, the clutch plate will stop rotation and be maintained against any rearward movement which might otherwise be produced by the action of the spring 84 by the drag produced by spring member 73.

In order that the pawl 76 will be moved out of the path of movement of the teeth as 69' of the ratchet collar 69 after the driving connection between the pawl and said collar is broken, the inner end as 76'' of the pawl is flat and arranged normal to the longitudinal axis of the pawl so that inasmuch as the rotary movement of the pawl and plate 71 is discontinued the instant the rear side or edge of the pawl is out of contact with the driving side wall of the ratchet slot 76', the ratchet tooth 69'' at the rear of the pawl will, during the continued rotation thereof, engage the center of the end 76'' of the pawl and cause said pawl to move radially outwardly a slight distance independently of the actuating arm 79, which action is permitted due to the fact that the pawl slot 76' is of greater length than the width of the adjacent portion of the arm 79 as previously described.

The manner of transmitting motion from the clutch plate 71 to the neutralizing plate 55 consists in providing a cam structure which in this instance comprises a pair of diametrically opposed pins 100 secured to the clutch plate and which extend upwardly through the opening 56 in the neutralizing plate 55, said pins and opening being covered by a washer 101 which separates said members from the lower pinion 40. The end walls as 56' of the opening 56 are spaced apart a sufficient distance to permit the free rotary movement of the pins 100 without said pins coming into engagement with said walls, while the side walls as 56'' of the opening 56 are spaced apart sufficiently to permit the required swinging movement of the plate 55 to bring the clutch 48 into clutching engagement with either of the pinions 40.

In other words, the pins 100 are arranged so as to be in the vertical plane passing through the axis of shaft 37 and pivot 57 when the clutch plate 71 is in the stationary position to permit the ready required swinging movement of the neutralizing plate 55, and at the same time, these pins are so diametrically spaced that when the plate is rotated one-half revolution, the pins during the rotation thereof will engage the side or cam walls 56'' of the opening 56 and restore the neutralizing plate 55 to its normal neutral position, with the longitudinal center line thereof extending through the axis of the shaft 37.

The hereinbefore-mentioned means for automatically controlling the rotation of the wringer rolls as the pressure on the rolls is released, may consist of any suitable means for operatively connecting clutch mechanism 67 with the pressure release mechanism incorporated in the wringer mechanism, and for this purpose, I have illustrated a well-known type of safety control mechanism for the wringer rolls which is readily adapted to control the operation of the clutch 67 and which is more clearly illustrated in Figures 1, 2, 4, 5, and 6. Briefly, this safety mechanism consists of the hereinbefore-mentioned U-shaped lock bar 15 which has the upper end of the side arms as 104 pivotally connected to the head 12 at 14 and extends downwardly from said pivot through the frame end 10 between rod 19 and a similarly disposed rod 105, with the lower ends thereof terminating near the bottom of the frame

end and connected by a transverse portion 106. Each arm has a longitudinal notch 107 in a vertical edge thereof for receiving the pin 19 therein and a cam surface 108 in the opposite edge adapted to engage the rod 105 as the lock bar 15 is being moved downwardly to the lowermost position to produce a swinging movement of the bar toward the rod 19 so that when the head 12 and lock bar 15 are in the lowermost position, the lower end of the lock bar will be in the outermost position, with the rod 19 registering in the notch 107 adjacent the lower end thereof.

A substantially horizontally disposed catch plate 110 is pivotally mounted at one end as at 111 to the cross member 11 in spaced relation to the lock bar 15. The other or free end of the catch plate extends beneath the transverse portion 106 of the lock bar and is yieldingly maintained in contact therewith by means of a compression spring 112 mounted on a guide rod 113 which is connected with the catch plate and cross member 11 for also limiting the upward movement of the catch plate. The catch plate 110 is provided with upwardly extending flanges 114 adjacent each longitudinal side thereof adapted, when the plate is in its uppermost position in contact with the transverse portion 106 of the lock bar 15, to abut against the inner side of said transverse portion and prevent inward swinging movement of the lock bar.

The catch plate is moved downwardly against the action of the spring 112 by a trip plate 116 which is pivotally mounted at 117 to the wringer frame. This trip plate is disposed in nearly a vertical plane, with the lower end thereof in engagement with the side flanges or abutment members 114 of the catch plate 110, while the upper end extends some distance above the pivot 117 and is in the path of movement of the lower end of a pair of rock arms 118 which extend upwardly through the frame end 10 and are pivotally mounted intermediate their ends upon the hereinbefore-mentioned rod 105. These arms 118 may, as shown, be connected by a cross member 119 which causes said arms to rock in unison.

The upper ends of the arms 118 terminate a short distance below the upper end of the frame end 10, and each is connected with a pin 120 which extends outwardly through an elongated slot 121 in the respective sides of the frame end 10 and connected at their outer ends to a slide plate 122 which is pivotally connected as at 123 to one end of a link 124. The other end of each of these links 124 is pivotally connected as at 125 to one end of a horizontally disposed safety release bar 126. These safety release bars 126 extend across respective sides of the wringer frame and are pivotally connected as at 127 to one end of a respective arm 128 which, in turn, is pivotally connected as at 129 to the corresponding side of the frame end 9.

The arms 118, trip plate 116 and the catch plate 110 are so related and mounted, that when the catch plate is in its uppermost position against the transverse portion 106 of the lock bar 15, the upper end of the rock arms 118 will be maintained in their innermost position, with the result that the safety release bars 126 will be maintained in their outermost position, as indicated by full lines in Figure 2 so that by pressing either one of the bars 126 inwardly, the upper ends of the rock arms 118 will be moved outwardly, as indicated by broken lines in Figure 2, which will cause the lower ends of these rock arms to move inwardly to rock the trip plate about the rod 117.

as a pivot and thereby press the catch plate 110 downwardly sufficiently to bring the abutment members 114 out of holding engagement with the lock bar 15.

- 5 As the catch plate 110 releases the lower end of the lock bar, said bar will then be caused to swing inwardly out of holding relation with the rod 19 due to the action of the pressure spring 24 and thereby permit the upward movement of 10 the lock bar and head 12 and release the tension of said spring upon the upper roll 8.

The downward movement of the catch plate 110 to release the lock bar 15 is utilized for actuating the detent 86 to bring the same out of 15 holding engagement with the abutment members of the clutch actuating arm 79. This movement is effected through the medium of a lever 132 which is disposed in the slot 2' of the case 2 intermediate the catch plate 110 and detent 86. 20 This lever 132 is pivotally mounted near the outer end thereof upon a rod 133 secured to the case 2. This lever has the rear end thereof contacting with the lower face of the catch plate 110, while the other end of the lever is provided with a 25 tongue portion 134 which is in engagement with a similarly constructed groove 135 in the rear end of the detent 86 so that when the inner end of the lever 132 is moved downwardly by the catch plate 110, the detent 86 will be rocked about 30 the pivot 87 against the action of the spring 88 out of holding engagement with the clutch actuating arm 79.

It will now be readily understood that when the lock bar 15 is maintained in its lowermost holding 35 position by the catch plate 110, as illustrated in Figure 5, and when the desired pressure is maintained upon the upper roll 8 through the medium of the tension screw 25 and spring 24, the rolls 7 and 8 may be rotated in either of two directions by the drive shaft 5 through the medium of the shaft 37 by manually manipulating the lever 53 to bring the clutch 48 into clutching engagement with one or the other of the pinions 40 depending upon the desired direction of rotation 45 of the wringer rolls.

When it is desired to again stop the rotation of the rolls, this may be manually accomplished by manipulating the handle 53 to return the clutch 48 to the neutral position intermediate 50 the pinions 40, but as this is a more or less laborious operation due to the friction between the clutch elements of the clutch member 48 and of the engaged pinion 40, the movement of the 55 clutch to the neutral position may be accomplished by slight physical effort by merely pressing the control rod 92 inwardly against the action of a spring 97 which may be effected from either side of the case to move the detent 86 downwardly against the action of the spring 88 out of holding 60 engagement with one or the other of the abutting members of the clutch actuating arm 79. As the detent 86 releases said arm, the clutch will be engaged by the action of the spring 84 in the 65 manner hereinbefore described so that the clutch plate 71 will be driven by the shaft 37.

As the clutch plate 71 rotates, the rotation of the pins 100 will return to a neutral position the 70 neutralizing plate 55 which has previously been swung to one side or the other of the normal position by the action of the gear 65 and segmental gear member 62 when the clutch 48 has moved from the clutching position to its normal position. As the plate 55 is thus swung inwardly, the clutch member 48 will be returned to its neutral position 75

through the medium of the roller 51, gear 65, segmental gear member 62 and the teeth 60. As the clutch actuating arm 79 is provided with abutment members at each end thereof, it is obvious that the clutch plate 71 will make but one-half of a revolution, when said plate will come to an at-rest position due to the detent 86 engaging one or the other of the abutment members 81 or 82 so that the pins 100 will normally lie in the longitudinal center line of the neutralizing plate 55 and thereby permit the free rocking movement of the plate when it is again desired to move the clutch member 48 into clutching engagement with one or the other of the pinions.

It is also obvious that the clutch 48 will be as 15 readily returned from the clutching engagement with one or the other of the pinions 40 to the neutral position by pressure upon one or the other of the safety release bars 126 in the manner hereinbefore described, and although I have shown 20 and described the preferred embodiment of my invention, I do not wish to be limited to the exact construction shown as various changes in the form, size and relation of the parts thereof may 25 readily be made, without departing from the spirit of this invention as set forth in the appended claims.

I claim:

1. In a control mechanism for the rolls of a clothes wringer, a safety device comprising releasable means for maintaining the rolls in pressure engagement, means for driving the rolls comprising a driving clutch element and a driven clutch element, manually operated means for normally controlling the engagement and disengagement of said clutch elements, and means actuated upon release of said releasable means for disengaging said clutch elements, said manually operated means being constructed and arranged substantially independently of said safety device 35 so that when the pressure on the rolls is released by the safety device and the manually operated means is in its clutch disengaging position, the latter may be operated to drive at least one roll without first restoring the safety device to its roll 40 pressure position.

2. In a control mechanism for the rolls of a clothes wringer, a safety device comprising releasable means for maintaining the rolls in pressure engagement, means for driving the rolls comprising a driving clutch element and a driven clutch element, manually operated means for normally controlling the engagement and disengagement of said clutch elements, said manually operated means having a neutral position in which the clutch elements are out of engagement and an operative position in which the clutch elements are in engagement, and means actuated by said releasable means for controlling the operation of said clutch elements, said manually operated means being constructed and arranged substantially independently of said safety device so that when the pressure on the rolls is released by the safety device and the manually operated means is 55 in neutral position, the latter may be operated to drive at least one roll without first restoring the safety device to its roll pressure position.

3. In a control mechanism for the rolls of a clothes wringer, driving mechanism for the rolls 70 comprising a fixed clutch element and a movable clutch element, manually operated means for moving said movable clutch element into and out of engagement with said fixed clutch element, a safety device comprising means for holding the 75

rolls in pressure engagement, means including a release element for releasing the pressure between the rolls, and means including a pivoted lever interconnecting said safety device and said movable clutch element for moving said movable clutch element out of engagement with said fixed clutch element when the release element is tripped, said manually operated means being restored to a neutral position as an incident to the disengagement of said clutch elements and being normally operable independently of the safety device to control the rotation of the rolls.

4. In a control mechanism for the rolls of a clothes wringer, driving mechanism including a drive shaft for the rolls, means comprising manually operated means for engaging and disengaging said drive mechanism, said manually operated means having a neutral and an operative position, a safety device comprising releasable means for holding the rolls in pressure engagement, control means for applying the power of the drive shaft to effect the disengagement of said driving mechanism, said manually operated means being restored to a neutral position as an incident to the disengagement of said driving mechanism, and means actuated upon release of said releasable means for setting said control means into operation.

5. In a control mechanism for the rolls of a clothes wringer, driving mechanism including a drive shaft for the rolls, means comprising manually operated means for engaging and disengaging the driving mechanism, said manually operated means having a neutral and an operative position, a safety device comprising releasable means for holding the rolls in pressure engagement, power operated means for effecting the disengagement of said driving mechanism, and means interconnecting said releasable means and said power operated means for setting the power operated means into operation when the safety device is operated, said manually operated means being restored to the neutral position when the driving mechanism is disengaged upon operation of the safety device.

6. In a control mechanism for the rolls of a clothes wringer, a unitary driving and reversing mechanism including a drive shaft for rotating the rolls, means comprising manually operated means for controlling the starting, stopping and reversing of the rolls, control means for applying the power of the drive shaft to disengage the driving mechanism, a second manually operated means for controlling the operation of said

control means, said first manually operated means being restored to a neutral position when said second manually operated means is operated to set the control means into operation and effect the disengagement of the driving mechanism. 5

7. In a control mechanism for the rolls of a clothes wringer, driving mechanism for the rolls comprising a drive shaft, a pair of driven clutch elements and a driving clutch element shiftable 10 into engagement with either of said driven clutch elements, manually operated means for engaging and disengaging said driving clutch elements from said driven clutch elements, control means for applying the power of the drive shaft to 15 disengage the driving clutch element from either of the driven clutch elements, and a second manually operated means operable from either side of the wringer for setting said control means into operation, said first manually operated means 20 being restored to a neutral position as an incident to the disengagement of said driving clutch element from either of said driven clutch elements.

8. In a control mechanism for the rolls of a clothes wringer, a driving and reversing mechanism for said rolls, means comprising manually operated means for controlling the starting, stopping and reversing of said rolls, a safety device comprising releasable means for maintaining the rolls in pressure engagement, power operated 30 means for effecting the disengagement of said driving mechanism, a second manually operated means, and means for setting said power operated means into operation either upon release of said safety device or upon operation of said second 35 manually operated means.

9. In a control mechanism for the rolls of a clothes wringer, a driving mechanism for the rolls, means comprising manually operated means for controlling the starting, stopping and reversing of the rolls, a safety device comprising releasable means for maintaining the rolls in pressure engagement, power operated means for effecting the disengagement of said driving mechanism and restoring said manually operated 40 means to a neutral position as an incident thereto, a lever interconnecting said releasable means and said power operated means for setting into operation said power operated means when said safety device is released, and separate manually 45 operated means for setting into operation said power operated means.

PETER EDUARD GELDHOF.

DISCLAIMER

2,086,497.—*Peter Eduard Geldhof*, Syracuse, N. Y. CONTROL MECHANISM FOR WRINGER ROLLS OF A WASHING MACHINE. Patent dated July 6, 1937. Disclaimer filed March 25, 1941, by the assignee, *Easy Washing Machine Corporation*.

Hereby enters this disclaimer to claim 8 in said Letters Patent.
